(57) **CLAIM**

The ornamental design for a liquid and steam separator as shown and described.

DESCRIPTION

Figure 1.1 is a front perspective of a liquid and steam separator used to separate mixtures of liquids and non-liquid materials from each other showing the new design;

Figure 1.2 is a front view of Figure 1.1;

Figure 1.3 is a right side view of Figure 1.1;

Figure 1.4 is a back view of Figure 1.1;

Figure 1.5 is a left side view of Figure 1.1;

Figure 1.6 is a top view of Figure 1.1; and

Figure 1.7 is a bottom view of Figure 1.1.

1 Claim, 7 Drawing Sheets
